UNITED STATES PATENT OFFICE.

HEINRICH POETTER, OF DUSSELDORF, GERMANY.

FURNACE PROVIDED WITH REGENERATIVE CHAMBERS.

1,100,985.

Specification of Letters Patent. Patented June 23, 1914.

Application filed December 22, 1913. Serial No. 808,104.

To all whom it may concern:

Be it known that I, HEINRICH POETTER, a subject of the King of Prussia, residing at 126 Grafenberger Allee, Dusseldorf, in 5 the German Empire, have invented certain new and useful Improvements in Furnaces Provided with Regenerative Chambers, of which the following is a specification, reference being had to the accompanying drawings.

This invention relates to improvements in furnaces that are provided with regenerative chambers, and wherein, while the waste gases and the fresh air flow alternately through one or other of these chambers, the direction of the flame within the furnace is maintained constant; and the invention has for its object to provide improved means for effecting the reversal of 20 flow of the heated air and waste gases, that is to say for causing each of these to flow alternately through one or other of the regenerative chambers.

Now according to this invention, the reversal of the direction of flow of the waste gases and the fresh air is effected by means of a slide provided with three ports, of which the central port is always used for supplying air to the flame, while the two 30 outer ports alternately conduct the waste gases to one or the other of the regenerative chambers.

The accompanying drawings illustrate by way of example one construction of apparatus according to this invention, Figure 1 showing the apparatus in vertical section and Fig. 2 in horizontal section on the line II-II of Fig. 1, showing the slide in one position, and Fig. 3 is a similar horizontal 40 section showing the slide in a second position. Fig. 4 is a vertical cross section on line 4-4, Fig. 2 and Fig. 5 a similar section on line 5-5, Fig. 3.

Air that enters through the reversing valve 45 *l* and which has already undergone preliminary heating in one of the regenerative chambers *g* or *h* is supplied to the flame by the flue *a*, while the waste gases escape through the flue *b* and through slide *c* into the other regenerative chamber and from 50 there through the reversing valve *l* and through the flue *m* to the stack. The reversal is effected by reversing first the ordinary reversing valve *l* and by means of the

slide *c* which is preferably arranged to run 55 on rails *c*₁ over a slide bed *c*₂, and is provided with three ports *d*, *e* and *f*. The apertures *k* in the regenerators *g* and *h* through which these are placed in communication with the flues *a* and *b* and one of 60 which is seen in Fig. 1, lie directly beneath the ports *e* and *f* of the slide in the position shown in Fig. 2, and the flues *a*, *b* are each bifurcated as shown at *a*¹, *a*², *b*¹, *b*², these branches being in alinement with the 65 ports *e*, *f*. When the slide is in the position shown in Fig. 2, the branches *b*₁, *a*₂, being closed by the slide as shown, the waste gases pass from the flue *b* through the port *f* of the slide into the regenerative 70 chamber *g*, while the fresh air simultaneously enters through the reversing valve *l* and passes through the regenerative chamber *h* and the port *e* into the fresh air supply flue *a*. When it is desired to effect reversal, the slide *e* is moved in the direction 75 of the arrow shown in Fig. 2, until, as shown in Fig. 3, the port *d* stands opposite to the flue *b*, whereupon the waste gases pass through the port *d* into the regenerative 80 chamber *h*, while the fresh air, after having been heated by passing through the regenerative chamber *g* will pass through the port *e* into the flue *a*. It will be seen that the bifurcation of the flues *a* and *b* in 85 proximity to the slide enables heated air to pass from one or other of the regenerators through the central port *e* to the air flue *a*, while the waste gases pass through one or other of the lateral ports *d*, *f* to the remaining regenerator. It will be seen, moreover, that the central port *e* of the slide 90 opens laterally toward the air flue *a* and is laterally closed toward the waste gas flue *b* while the side ports *d* and *f*, on the contrary open laterally toward the waste gas flue *b*, and are laterally closed toward the air flue *a*.

A reversing device in accordance with this invention is suitable for use in any furnace 100 wherein it is desirable that while the direction of the flame remains constant, a reversal of the regenerative chambers should take place at certain stated intervals. Regenerative furnaces in which the direction 105 of the flame remains constant, when provided with a device in accordance with this invention are especially suitable for use in

connection with open hearth furnaces for reheating the material under treatment in rolling mills.

What I claim is:—

- 5 1. In a furnace provided with regenerative chambers, a slide bed wherein there are provided orifices communicating with said chambers, air and waste gas flues each provided in proximity to said slide bed with a bifurcated portion the branches of which are in alinement with said orifices, and a slide movable upon said slide bed from one to the other of two positions, said slide having formed in it a central port and two side ports the central port and one or other of the side ports being situated in either position of the slide directly above aforesaid orifices, and the central port being in alinement and communication with one of the branches of the air flue, while the side port situated above an orifice is in alinement and communication with one of the branches of the waste gas flue.
- 10 2. In a furnace provided with regenerative chambers, air and waste gas flues in alinement with each other, and each provided with bifurcated portions the branches of which are also in alinement with each other, and a slide movable transversely of said flues from one to the other of two extreme and operative positions, and provided with a central and two side ports of which the central port is open laterally toward the air flue and closed laterally toward the waste gas flue, while the side ports are open laterally toward the waste gas flue and closed laterally toward the air flue, said ports being so spaced that when the slide is in either extreme position, two of its ports are in alinement with the bifurcated branches of the flues.
- 15 3. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed, and the ports in the slide being so spaced that the central and one or other of the side ports can be brought into juxtaposition and communication with aforesaid ports in the slide bed, an air supply flue and a waste gas flue that are in communication with the interior of the furnace, and that when the slide is in the aforesaid position are thereby respectively placed in communication with the regenerative chambers through the aforesaid central and side port of the slide.
- 20 4. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed, and the ports in the slide being so spaced that the central and one or other of the side ports can be brought into juxtaposition and communication with aforesaid ports in the slide bed, an air supply flue and a waste gas flue that are in communication with the interior of the furnace, and that when the slide is in the aforesaid position are thereby respectively placed in communication with the regenerative chambers through the aforesaid central and side port of the slide.
- 25 5. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed, and the ports therein being adapted to be put in communication with passages located adjacent to three different faces of the slide.
- 30 6. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.
- 35 7. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.
- 40 8. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.
- 45 9. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.
- 50 10. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.
- 55 11. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.
- 60 12. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.
- 65 13. The combination with a furnace provided with two regenerative chambers arranged side by side, of a slide bed arranged transversely of said chambers and having formed in it a pair of ports arranged side by side and respectively communicating with said chambers, a slide furnished with a central and two side ports arranged side by side, said slide being movably mounted on said slide bed and the ports therein being adapted to be put in communication with passages located adjacent to three different faces of the slide, two of these passages leading horizontally in opposite directions and being respectively adapted for the supply of fresh air and the escape of waste gas while the third of the passages leads vertically downward toward a regenerating chamber.

by side, said slide being movably mounted on said slide bed, the central port being adapted to serve for the supply of fresh air and the two side ports for the passage of the 5 waste gases.

8. The combination with a furnace provided with two regenerative chambers arranged side by side, of a slide bed arranged transversely of said chambers and having 10 formed in it a pair of ports arranged side by side and respectively communicating with said chambers, a slide furnished with a central and two side ports arranged side by side, said slide being movably mounted 15 on said slide bed, and the ports in the slide being so spaced that the central and one or other of the side ports can be brought into juxtaposition and communication with aforesaid ports in the slide bed, an air supply flue and a waste gas flue that are in 20 communication with the interior of the furnace, and that when the slide is in the aforesaid position are thereby respectively placed in communication with the regenerative 25 chambers through the aforesaid central and side port of the slide, the communications between said valve ports and said air supply flue, waste gas flue, and said regenerative chambers being situated respectively in 30 two opposite horizontal directions and a vertically downward direction.

9. The combination with a furnace pro-

vided with two regenerative chambers arranged side by side, of a slide bed arranged transversely of said chambers and having formed in it a pair of ports arranged side 35 by side and respectively communicating with said chambers, a slide furnished with a central and two side ports arranged side by side, said slide being movably mounted on said slide bed, and the ports in the slide 40 being so spaced that the central and one or other of the side ports can be brought into juxtaposition and communication with aforesaid ports in the slide bed, an air supply flue and a waste gas flue that are in 45 communication with the interior of the furnace, and that when the slide is in the aforesaid position are thereby respectively placed in communication with the regenerative chambers through the aforesaid central and 50 side port of the slide, the communications between said valve ports and said air supply flue, waste gas flue, and said regenerative chambers being situated respectively in two opposite horizontal directions and a 55 vertically downward direction.

In testimony whereof I affix my signature in the presence of two witnesses.
